CLAIM

The ornamental design for a door gate, as shown and described.

DESCRIPTION

FIG. 1 is a top, front and right side perspective view of a door gate, showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top, front and right side perspective view showing the door gate with its inner small door in close state;

FIG. 10 is an enlarged view of portion 10 in FIG. 1;

FIG. 11 is an enlarged view of portion 11 in FIG. 1;

FIG. 12 is an enlarged view of portion 12 in FIG. 1;

FIG. 13 is an enlarged view of portion 13 in FIG. 2; and,

FIG. 14 is an enlarged view of portion 14 in FIG. 8.

The evenly dashed broken lines illustrate portions of the door gate that form no part of the claimed design.

The unevenly dashed broken lines define the boundaries of enlarged views and form no part of the claimed design.
